(57) **CLAIM**

The ornamental design for a rack, as shown and described.

DESCRIPTION

FIG. 1 is a perspective view of a rack showing my new design;

FIG. 2 is front elevation view thereof;

FIG. 3 is a back elevation view thereof;

FIG. 4 is a left side view thereof;

FIG. 5 is a right side view thereof;

FIG. 6 is a top plan view thereof; and,

FIG. 7 is a bottom plan view thereof.

The broken line showing of the rack is for the purpose of illustrating article and forms no part of the claimed design.
